UNITED STATES PATENT OFFICE

1,961,002

FLAT BED WEB PRINTING PRESS

Leon E. La Bombard, Waltham, and Melvin H. Sidebetham, West Newton, Mass., assignors to Specialty Automatic Machine Co., Chelsea, Mass., a corporation of Massachusetts

Application March 11, 1931, Serial No. 521,652

5 Claims. (Cl. 101—294)

This invention relates to printing presses of the type known as flat bed printing presses, and has particular reference to that type of such presses which prints an impression on a long strip or web of paper or other material as it is fed through the machine.

In all forms of printing presses of the flat bed type of which we are aware, the mechanisms for intermittently moving the various elements consist for the most part of step-by-step progressive mechanisms, such as pawls and ratchets. Such mechanisms, while quite efficient at low speeds, are not sufficiently positive to be employed in high speed automatic printing machines. Furthermore, such mechanisms actuate the driven element at one speed during its operation, which requires that the inertia of the parts which are stationary for awhile must be immediately overcome by the member which causes their next movements. This condition also exists at the end of the movement when the parts must be brought to a stop at a predetermined point. Mechanisms which operate under these conditions necessarily sustain heavy loads due to excessive friction which causes excessive wear and frequent breakdowns. Furthermore, the feeding of a web of paper under such conditions is impractical at high speeds, due to the inaccuracy of proper register. Therefore, a particular object of our invention is to provide a printing press with mechanisms of the kind hereinafter described that will initiate movement of the moving parts slowly and accelerate them until they attain their maximum speed, at which speed they are maintained for a predetermined length of time and are then retarded until they come to rest for a similar predetermined period. One of these mechanisms drives the printing unit, another the inking unit, and still another the paper feeding unit. These movements are accomplished by mechanisms in which the parts are always in operative relation, and are entirely positive in their actions during each complete cycle of operation of the press. The mechanisms referred to are driven from a source of power common to all, and are therefore constantly synchronized.

Another object of our invention is to provide a printing press of the flat bed type which includes means for imparting intermittent movements to the various elements, with mechanisms which, because of their structure and operation, will permit the attainment of much higher speeds of all primary elements of the press.

Another object of our invention is to provide a mechanism for driving the elements of a print-

ing press in constantly maintained synchronism between said elements, and at the same time allow for adjustment of the speed of those elements that it is necessary to vary.

Another object of our invention is to provide an improved simple and efficient inking mechanism for the printing element.

Another object of our invention is to provide for the quick removal of rolls, plates, and other parts that are used for supplying and distributing the ink, whenever the cleaning of such parts is necessary.

With the hereinbefore mentioned objects in view, and others hereinafter explained, the invention consists in the construction and combinations of parts substantially as hereinafter described and claimed.

Of the accompanying drawings:—

Figure 27 is a detail sectional view on the line 27—27 of Figure 23.

20 Similar reference characters indicate similar parts or features in all of the views.

Mounted on a suitable base 21 are side frame members 22, 23, 24, 25 for supporting the different mechanisms hereinafter described. The two side members 22 support a roll of paper 26 from which the web P is drawn by the take off rolls 247. Said side frame members also support the tensioning mechanism 27 similar to the mechanism described in Letters Patent No. 1,727,203, issued September 3, 1929 to us.

30 The right-hand side frame member 23 carries bearings 28 (Fig. 2) in which is journaled the shaft 29, said shaft having a friction clutch 30 by means of which rotation is transmitted to the said shaft from another portion of the clutch that

35 is affixed to the sprocket 31. Said sprocket is connected by means of chain 32 to a sprocket 33 of the shaft of a motor 34. The operation of this clutch to start or stop the press is controlled by a hand lever 35 (Fig. 1) through suitable link-

40 age to a rock shaft 36 extending transversely of the machine. On the end of the rock shaft 36 adjacent to the clutch 30 is fixed a forked lever 37, the forked portion of which fits over the usual pins of the sliding member of the clutch 30.

45 Movement of the lever 35 therefore causes the clutch members to be engaged so that the shaft 29 is driven.

To facilitate an understanding of the press, a preliminary description, or outline, thereof will 50 now be given.

When the press is started, the web of paper to be printed is first unwound from the roll 26 by the rolls 247 in order to supply said web freely to the printing mechanism. The web so freed 55 from the roll 26 is drawn or fed at varying speeds of travel by rolls operated by special gearing at the other end of the press. While said varying feed of the web is being effected, the printing head 84 (Fig. 6) which is in the casing 56 (Figs. 60 2 and 3) and which carries the type matter, is in its uppermost position and at rest. Said printing head is operated at intermittently and alternately varied speed of movement by gearing mechanism including the gear 69, in said casing.

65 As soon as the printing head comes to rest in its raised position, one of the three sets of inking rolls 105 (Fig. 6) passes under the type while the other two sets are receiving a fresh supply of ink and distributing it.

70 Figure 6 illustrates the head 84 in its upper position at rest, and the three sets of inking rolls 105 all in the position where they are travelling at their highest speed, and said head remains in its upper position while a set of the rolls 105 completes travel under it. Then the speed of travel

of the inking rolls slows down, under the control of gearing including the gears 75, 78, and shaft 79 (Figs. 3 and 5).

The important features of the press are the mechanisms which vary the speed of travel of the web, the speed of movement of the vertically moving printing head, and the speed of movement of the inking rolls, in order to attain high speed of operation of the press without causing any sudden starts of operation.

80 The detailed description of the entire press will now be given.

On one end of the shaft 29 is fixed a sprocket 38 (see dotted lines in Fig. 2) which is connected by a chain 39 to a sprocket 40 of the shaft 41. The bearings for the shafts 29 and 41 at one end are in a housing 42 which also serves to cover the sprockets 38 and 40 and chain 39. This housing is fixed to the side frame member 22.

90 Resting on and slidable along the top of the side frame members 23 (Figs. 1, 2, 3, 4, 5, and 6) are side plates 43 and 44 of the printing unit. These plates are rigidly united by the overhead bridging member 45 and printing bed or platen 46. On the sides of the frame members 23 are 100 fixed guide bars 47 the upper edge of each of these bars extending upwardly above the side frame members 23, thus forming with the tops of the latter a track along which this entire unit may be moved to any desired position. This 105 movement is accomplished by rotating the shaft 48 which has gear teeth cut on both ends thereof of which teeth mesh with cooperating rack teeth cut on the upper surfaces of the guide bars 47. When the printing unit is located in the correct 110 position it is clamped by means of a screw 49 (Figs. 3 and 6) threaded into the side plate 43 and the end of which abuts a bell crank lever 50. This lever 50 is pivoted at 51 in a bracket 52 and its horizontal arm extends under and inwardly 115 projecting ledge on the left side frame 23. Actuation of the screw 49 inwardly by means of its knob clamps the said ledge between the horizontal arm of the bell crank lever 50 and the bottom surface of the side plate 43.

120 Slidable on and keyed to the shaft 41 (Figs. 3 and 5) is a mitre pinion 53 in mesh with a mitre gear 54 on the shaft 55. The shaft 55 is journaled in a gear box cover 56 and extends through to the outside of said box and has mounted there-

125 on a sprocket 57. The shaft 55 has also keyed to it a double sprocket 58 that is connected by a chain 59 to a double sprocket 60 keyed on the shaft 61, which is journaled in the side plate 44 and gear box cover 56. A driving gear 62 is 130 mounted eccentrically on the shaft 61. Also mounted eccentrically on the shaft 61 is an eccentric 63 which is concentric with the gear 62. Said gear 62 and the eccentric 63 are held in this relation by a bolt 64 which passes through the driving gear 62 and eccentric 63 and is threaded into the double sprocket 60.

135 An eccentric strap 65 is rotatably mounted on the eccentric 63 and at its extremity has rotatably mounted thereon an intermediate gear 66 by means of a bolt 67 that is threaded into the rock-lever 68, the latter being fixed to the driven gear 69. This driven gear 69 and the lever 68 are keyed to the crank shaft 70 which, through mechanism to be described in detail, actuates the printing head 84.

140 The operation of this mechanism is as follows:—The shaft 61 being rotated in a counter clockwise direction as viewed in Fig. 5 moves the printing press crank-shaft 70 intermittently in the same direction. The velocity of this crank-

150

shaft is accelerated from rest (which takes place for approximately 78° of the revolution of shaft 61) to maximum and is retarded to rest during one revolution of the shaft 61. One revolution 5 of the shaft 61 causes the printing press crank-shaft 70 to complete one revolution and one rest period.

A similar mechanism composed of a driving gear 71, eccentric 72, bolt 73, eccentric strap 74, 10 intermediate gear 75, bolt 76, rock lever 77, driven gear 78, and chain drive shaft 79, imparts an intermittent rotation to the chain drive shaft 79 identical with the described intermittent motion imparted to the printing press crank-shaft 70. 15 However, these two motions are 180° out of time with each other so that when the printing press crank-shaft 70 is rotating at its maximum speed of 78° the chain drive shaft 79 is stationary for 78° and vice versa. The operation of these intermittent driving means is described more in detail in U. S. Letters Patent No. 1,393,219 issued Oct. 11, 1921 to George I. Hohl. In each instance a complete revolution is imparted to the crank-shaft 70 of the present invention and to the 20 chain-drive shaft 79.

It will now be understood that we have provided a web printing press in which the travel of the web, the movement of the printing head, and the movements of the inking rolls, all start 30 from zero or near it, then increase to highest speed, and then slow down again, thereby attaining high speed of complete operation of the press without any sudden starts of operation that would cause strain on, or undue wear of, the 35 mechanism.

The crank-shaft 70 extends across the printing machine and is journalled in bearings 80 (Figs. 3 and 6) suspended from the bridging member 45, and is provided with two crank portions 81 (Fig. 3). Rods 82 connect the crank portions 81 with pins 83 which are mounted in the printing head 84. Upwardly extending arms 85 project from the printing head 84 and are provided with V shaped ribs 86 (Figs. 10 and 11) that 45 slide in V shaped grooves 87 of guide blocks 88. Said guide blocks are secured by means of bolts to inwardly projecting ribs 89 on the side plates 43 and 44. Adjustment of said guide blocks 88 is effected by screws 90. A complete revolution 50 of crankshaft 70 moves the entire head down and up once where it remains while the driving mechanism is imparting no rotation to the crank-shaft 70.

On the forward end of the printing head 84 (Fig. 6) is rigidly mounted a fixed cleat 91 which cooperates with a pivoted cleat 92 for holding the type chase C rigid to the printing head 84 which is provided with a concave groove along its rear end which receives a cooperating convex ridge 60 along the inside surface of the cleat 92, the combined groove and ridge forming a pivot for the cleat 92 to enable it to clamp the type chase by applying pressure to said cleat above its pivot. Bosses 93 (Figs. 6 and 12) integral with the printing head 84 have vertical portions to which plates 94 are attached by screws, said plates forming guideways between the tops of the bosses 93 and the under surfaces of the plates 94 for the wedge blocks 95. A screw 96 with right and left hand threads there on is threaded through the wedge blocks 95 and extends out through the side of the machine, and is provided with a knob 97 for rotating it. Bearings 98 are also mounted on the bosses 93 and have slide rods 99 passing there- 70 through one end of each rod 99 abutting against

the oblique face of each wedge block 95 and the other end of each rod 99 abutting against a lug 100 projecting upward from the pivoted cleat 92. Rotation of the knob 97 in one direction will cause a movement of the wedge blocks 95 so that they move the rods 99 outwardly against the lugs 100, moving them outwardly also until the lower portion of the cleat 92 engages and clamps the side of the type chase C against the fixed cleat 91. 80

The chain drive shaft 79 extends transversely of the printing press and has its bearings in the side plates 43 and 44. Mounted on this shaft are sprockets 101, and in alignment with the latter are grooved blocks 102 (Figs. 3 and 6) on the bridging member 45, and idler sprockets 103 rotatably mounted on the side plates 43 and 44. Two type inking roll chains 104 pass over the sprockets 101, grooved blocks 102, and idler sprockets 103; and carried by the chains 104 are type inking rolls 105. Each chain 104 is provided at three points along its length with two or more links 106 which are substituted for the standard links. Passing through a slot 107 (Fig. 14) in each of these links is a rod 108 each of which extends transversely of the machine, thus uniting the two chains 104. 90

The inner raceways of ball bearings 109 are mounted on the rods 108 and their outer raceways are housed in cupped sleeves 110 which are in turn fixed to sleeves 111 on which are mounted rubber or composition type-inking rolls 105. The ends of the rods 108 are recessed to accommodate springs 112 one end of each of which is hooked over the pin 113 driven through the rod 108 and 110 across the recess in its end. The other end of the spring 112 is hooked around a pin 114 which is rigidly mounted across a thimble 115 and passes through slots 116 in the rod 108. The links 106 are provided on their outside surfaces with 115 recesses 117, (Fig. 13) adjacent to the ends of their slots 107. The inner ends of the thimbles 115 are held in the recesses 117 by springs 112 thus forming a connection between the chains 104 and the rolls 105 whereby the rolls 105 can be 120 readily disconnected from the chains 104 by pulling the thimbles 115 out until their ends have become disengaged from their recesses 117, whereupon the roll unit can be lifted from the chain. This structure enables each roll to be 125 quickly released, and a new one to be positively locked in its place.

The grooved blocks 102 are secured to the overhead bridge 45 by bolts that are located in the slots 118 in the lugs 119 (Figs. 1, 3, and 5) so that 130 by raising the grooved blocks the chains may be tightened as necessary.

Vertically adjustable tracks 120 (Figs. 6 and 15) are provided to maintain the rolls 105 against the type as said rolls pass under the uplifted 135 printing head during their type inking operation. One of these tracks may be hinged as shown to facilitate threading of the paper through the machine.

Upon completion of each rotation of the shaft 140 70 (the printing head 84 being raised at this time) one set of the inking rolls 105 passes under and rolls in contact with the surface of the type to be inked. The rolls then slow down to come to a complete stop at a point beyond the printing head 84 which then starts down on its impression stroke and then up again to normal position, where it dwells. 145

The structure described enables high speed operation to be maintained without liability of the 150

inking rolls melting as they sometimes do in hot weather. This advantage is due to the provision of the three sets of inking rolls 105 each of which, while in contact with the type form, travels but 5 a very short distance relatively to its total distance of travel.

The bed 46 of the printing machine is bolted to the side plates 43 and 44 and has an upwardly extending portion (Fig. 17) located directly under 10 the printing head. This upwardly extending portion has a frame 121 surrounding it (Fig. 16) in which frame is mounted a roll 122 to which is secured the usual pad of paper 123 or other resilient material that backs up the web of paper during 15 the printing operation. This pad 123 is maintained taut across the top of the bed 46 by means of a pawl on the frame 121 that cooperates with a ratchet fixed to the roll 122. The other end of the pad is fixed to the opposite side of the frame 20 121. This frame fits over the bed quite tightly and is lifted off by means of a rod 124 (Fig. 3) having a handle by which it may be pushed inwardly against the pressure of a spring 125. Said rod is connected to a bell crank lever 126 the 25 upper end of which is under the frame 121 so that inward pressure on the handle of the rod will lift the frame 121 off the bed 46. This provides for a quick release of the frame and its paper "make ready" 123 when a new one is necessary.

30 The sprocket 57 mounted on the shaft 55 is connected by means of a chain 127 (Figs. 2 and 3) to a sprocket 128 on the shaft 129. A pinion 130 (Fig. 5) on this shaft drives the shaft 131 mounted in brackets 136, 137 (Figs. 1 and 2) through gear 35 132. Sprockets 133 (Fig. 6) on the shaft 131 are connected by chains 134 to sprockets 135 which are rotatably mounted on the brackets 136, 137. Said brackets are bolted to the side plates 43, 44. The mountings for the sprockets 135 are adjust- 40 able to allow for take-up in the chains 134. Said chains are backed up on the inside by adjustable grooved guideways 138. The chains 134 also carry two sets of ink distributing rolls 139 similar in construction and mounting to the type inking 45 rolls 105.

An idler gear 140 (Fig. 5) is interposed between the gear 132 on the shaft 131 and the gear 141 which is loosely mounted on the inking roll shaft 142. This idler gear is mounted on a bracket 143 which is swiveled on the shaft 131 and clamped by 50 a bolt to the bracket 137. The bracket 143 has a slot through which said bolt passes permitting change of gearing on the shaft 142 to vary the speed of the inking roll 144. A pawl 145 is 55 pivoted on the inside of the gear 141 and engages a ratchet wheel 146 fixed to the inking roll shaft 142. Said pawl 145 is held in engagement with the ratchet wheel 146 by means of a spring-pressed plunger 147 (Fig. 9) which has a ball 60 point that fits in a cup-shaped recess in the pawl 145. Said pawl can be swung out of engagement with the ratchet for manual rotation of the inking roll.

The inking roll shaft 142 is journalled in bearings 148 mounted on a cross bar 149 (Fig. 5) which is rigidly mounted on the brackets 136 and 137 by bolts. Said bearings 148 also serve as ends for an ink reservoir.

A flexible plate 151 is clamped at its rearward 70 portion to the cross bar 149 and the plate 150 by bolts 152 (Fig. 4) extending through suitable slots in the cross bar 149, and through the flexible plate 151 and into the clamping plate 150. The forward portion of this plate 151 extends under the 75 inking roll 144 and is held in close relation with

the face of said roll by means of adjusting screws 153 (Fig. 6). The space between the flexible plate 151 and the surface of the roll 144 determines the thickness of the film of ink which the roll 144 picks up and delivers to the ink distributing rolls 139. Secured to the end of the inking roll shaft 142 opposite the gear 141 is a ratchet wheel 154 (Fig. 7) which cooperates with a pawl 155 on the hand lever 156 to afford means for manually operating the roll 144.

To support the ink-distributing plates 164, 165 in a manner to enable them to be quickly released for cleaning, cross guide bars 157 (Figs. 3, 6, and 18) are adjustably mounted on angle pieces 158 which are fixed to the side plates 43, 44 by screws. The sliding bars 159 have ears 160 that fit over the cross guide bars 157. Strips 161 span the ears 160 and are secured to said ears by means of screws thus forming a guideway on which the bars 159 slide over the guide bars 157.

The upper ears 160 of the sliding bars 159 are provided with extended portions 162 (Fig. 19) that engage under the hook members 163 on the backs of the intermediate distributor plate 164 and the final ink-distributing plate 165. The 100 lower ears 160 of the sliding bars 159 that are nearest the frame side plate 43 are slotted at 166. Lugs 167 on the back of the intermediate distributor plate 164 and the final ink distributing plate 165 fit in said slots. Clamping screws 105 168 (Fig. 3) are threaded into the outside members of the forks and said clamping screws extend through the side plate for quick hand operation. The points of the clamping screws 168 are conical and engage conical recesses 169 (Fig. 110 19) in the lugs 167. To attach either of the plates 164 or 165 the hook members 163 on the back of said plates are hooked over the extended portions 162, and the lugs 167 are placed in the slots 166 and clamped in place by the clamping 115 screws 168 entering the conical recesses 169. This firmly secures the plates 164 and 165 to the sliding bars 159. The final ink-distributing plate 165 is held stationary by a suitable screw 170 (Fig. 6) securing the sliding bar 159 to the cross 120 bar 157. Its quick release is effected in a manner similar to that of the distributor plate 164.

As clearly illustrated in Figure 6, the ink distributing plates 164, 165 are so positioned relatively to the printing form C, and the three sets of travelling inking rolls 105 are so spaced relatively to each other and to the form C and plates 164, 165, that while one set is inking the form, another set is taking ink from the plate 164, and another set is coating with the secondary plate 130 165. In other words, the three sets of inking rolls are performing different acts at the same time.

Mounted on the inside surfaces of the brackets 136, 137 are plates 171 (Figs. 4 and 20) which serve as supporting means for spring-pressed pintles 172 at each end of the rod 173. Bearings 174 (Figs. 4 and 6) are fixed to the back of the ink distributing plate 175 and the rod 173 is mounted in said bearings 174 with a sliding fit. A rod 176 is also mounted on the ink distributing plate 175 in a similar manner. Said rod 176 has no spring-pressed pintles at its ends but said ends are merely turned down to a reduced diameter to fit in the groove 177 of the bearing plates 171. Thus the plate 175 is slidably mounted on the rods 173, 176 and is quickly detachable by pressing the pintles 172 inwardly on the upper rod 171 and lifting the lower rod 176 out of its grooves 177. However, when in position the ink distrib- 150

utting plate is firmly held against rearward movement when the rolls 139 contact with it.

On the end of shaft 131 opposite the gear 132 and outside the bracket 136 is fixed a pinion 178 (Fig. 7), said pinion engaging a gear 179 mounted on a stud shaft 180 which has its bearing in the bracket 136. Also mounted on the shaft 180 is a grooved cam 181. A bearing 182 provides a journal for the shaft 183 and is mounted on bracket 136. To the upper portion of the shaft 183 is fixed an arm 184 having a roll 185 engaging the groove in the cam 181. To the lower portion of this shaft is fixed a lever 186 (Fig. 8) one end of which is pivotally connected to a rod 187 which is secured at 188 to the plate 175. The opposite end of the lever 186 is pivotally connected to a link 189 which extends inwardly through the side plate 42 and at its inner end is connected by means of a pin 190 and a bracket 161 to the strip 161. Said strip being fixed to the intermediate distributing plate 164 as has been described, it is evident that rotation of the cam will cause the shaft 183 to oscillate thereby reciprocating the ink distributing plate 175 and the intermediate ink distributing plate 164.

The shaft 41 extends through the gear box rearwardly of the machine and has bearing in a chain box 192 (Figs. 2, 21 and 22) which is mounted on the side frames 23 and 24. In the rearward end of said shaft 41 is a hole in which the key carrier 193 is inserted. This key carrier has a recess 194 in which is pivoted a spring-pressed key 195 which extends outwardly through a slot 196 in the shaft 41 and into a keyway 197 of the particular sprocket 198 that is selected for the speed desired. Washers 199 are placed between the sprockets 198. As shown in Figure 22 the shaft 41 is driving the middle sprocket 198, and the two other sprockets are disconnected from the shaft. The key carrier 193 may be moved in or out by the knob on its outer ends and the key will be withdrawn from its illustrated driving connection with the middle sprocket. The level faces on the ends of the key 195 will ride over the washers 199 thereby compressing the spring which normally maintains the key 195, in engagement with one of the keyways 197. Continued movement of the key carrier 193 will allow the key 195 to snap into the next keyway 197 under the pressure of its spring. Thus any one of these three sprockets 198 may be keyed to the shaft 41 at will. The sprockets 198 are connected by chains 200 to sprockets 201 keyed on a shaft 202, it will be seen therefore that the shaft 202 can be driven at any selected one of three speeds.

At an intermediate point of the driven shaft 202 toward the rear of the machine from the chain box 192 power is taken off by means of mitre gears 203, (Figs. 2, 23 and 24), the driven member of which is carried by a shaft 204 in a gear box 205 which is bolted to a side frame member 25. In said gear is a similar mechanism to that which drives the crank shaft 70 and the chain drive shaft 79 as hereinbefore described. It is composed of a disc 206 fixed on the shaft 204, driving gear 207, eccentric 208, bolt 209, eccentric strap 210, intermediate gear 211, bolt 212, rock lever 213, and driven gear 214. This latter gear 214 is carried by shaft 215 which extends transversely of the machine and through the opposite frame member 25 and which shaft has secured to its end a pinion 216, said pinion being in mesh with an idler gear 217 (Figs. 23 and 25)

carried by a lever 218 as indicated at 219. Said lever 218 is pivoted at 220 and locked in place by means of a bolt 221. The idler gear 217 engages a driven gear 223 carried by a paper feed-roller shaft 223. This gearing therefore constitutes a means for varying the speed of rotation of the paper feed roller 224 and thereby intermittently feeding the web to varying degrees of advance relatively to the speed of the vertical reciprocation of the printing head 84. As has been explained, the shaft 202 is constantly driven at any of a selected plurality of speeds. Since said shaft 202 drives the paper feed roller 224 at intermittent varying speeds by means of the speed-changing gearing similar to that which drives the crank shaft 70, as just described, the intermittent feed of the paper web is always under absolute control by the machine itself in accord with the intermittent and varying speed of operation of the other parts of the machine. Therefore it ensures perfect registration of the printing on and along predetermined areas of the traveling web of paper. Crosswise of the machine and bolted to the two frame members 25 is a cross bar 225 (Figs. 1, 23 and 27) having a dovetail slide 226 formed thereon throughout part of its length. This slide serves as a suspension means for the pressure roll carriages 227 in conjunction with cleats 228 bolted to the carriages 227. Pivoted on pins in the carriages 227 are idler roll frames 229 in which are mounted, on shafts 230, the idler tension rolls 231. Springs 232 press on the rearward ends of the idler roll frames 229. Said springs 232 are housed in recesses in the carriages 227 and the tension of each is adjustable by a screw. Extending transversely of the machine under the rearward end of the idler roll frames 229 is an eccentric portion 233a of a shaft 233 supported in the side frames 25. Said shaft 233 also has fixed thereto a gear 234 (Figs. 23 and 26) engaging a rack 235 which is manually raised or lowered by a hand lever 236. The rack 235 is held in engagement with the gear 234 by a cage 237 which fits around said shaft and through which the rack passes. Said rack is also guided at its top by a bracket 238. Movement of the hand lever 236 therefore rotates the shaft 233 causing the eccentric portion 233a to lift the rearward end of the idler roll frames 229 and remove the pressure between the feed roll 224 and the idler rolls 231, thereby manually disconnecting the paper feed and stopping the paper from feeding. The rotation of the paper feed roll 224 being intermittent and adjustable, paper can be fed (when the printing press head 84 is raised) any desired distance depending on the nature of the work to be done. A brake 239 (Figs. 23 and 24) is provided to co-operate with a drum 240 on the feed roll shaft 223 to prevent overrunning of the roller 224. The brake 239 is actuated by an eccentric strap 241 fitting over an eccentric 242 on the shaft 202, and from which a rod 243 extends down through the rear end of the brake lever and has a ball on its end that lifts one end of the brake lever when the eccentric 242 raises the eccentric strap 241. This eccentric is located on the shaft 202 in such position as to apply the brake at the instant that the paper feed roll stops.

A chain 244, a portion of which is illustrated in Figure 24, transmits power from the shaft 202 to a variable speed of transmission device 245 of standard make to supply power if desired to a paper roll-up device 246 and also to a roll-off device 247 at the forward end of the machine.

Paper perforating units 248 of a known type are driven by the shaft 292 synchronizing their operation with the rest of the machine. Means of known type are also provided at 249 for shearing the edges of the paper.

The positions of the perforating and shearing units are adjustable along the length of the machine by means similar to that used for the printing unit.

10 The side frames 23 may be as long as necessary to support the number of printing units necessary for multi-colored printing work. The machine is shown broken away in Figs. 1 and 2 and any number of printing stations may intervene between these breaks. However only one is shown on the drawings, as a description of the one unit will suffice for any plurality utilized.

The operation of the printing press is as follows:

20 The hand lever 35 is operated to throw the clutch 30 in, thereby causing the shaft 29 to rotate. Rotation is thus imparted to the shaft 41 from the shaft 29 by the chain 39. The mitre pinion 53 and gear 54 drive the shaft 55 which in turn drives the shaft 61 in a counter clockwise direction by means of the chain 59. The eccentric 63 moves the intermediate gear 66 up and to the left from its position shown in Figure 5 in an orbit around the gear 69. At the same time 30 the driving gear 62 is rotating eccentrically with the shaft 61 thereby rotating the intermediate gear 66 clockwise on its own axis. This in turn starts to roll around the driven gear 69 in a planetary movement but soon the planetary movement 35 of the gear 66 becomes less than its rotative movement and as a result rotation in a counter clockwise direction is imparted to the driven gear 69 and thence to the crank shaft 70. The movement of the shaft 70 starts slowly and gradually accelerates to its maximum speed which it maintains for approximately 78° of rotation of the shaft 61 and then slows as the intermediate gear 66 is moved down and to the right by the eccentric 63, until said gear 66 comes to the end of its 45 stroke at which point it is imparting no motion to the crank-shaft 70.

The chain drive shaft 79 is driven from the shaft 61 in a similar manner with a similar motion, but one-half cycle out of time with the previously described mechanism.

50 The inking roll 144 rotating in a counter clockwise direction carries ink on its surface into the path of the ink distributing rolls 139 carried by the chains 134. These chains are driven from the shaft 55 through the sprockets 57 and chain 127 to the sprocket 128 on the shaft 129, thence by the pinion 130 to the gear 132 on the shaft 131. Said shaft 131 carries the driving sprockets 133 of the chains 134. The rolls 139 are driven around their path at a constant speed but are so located on their chains 134 that they never come in contact with the type inking rolls 105 on the chain 104. As the rolls 139 roll over the inking roll 144 they pick up ink that is distributed over the surface of the roll 139 by the ink distributor plate 175. Ink is then carried to the ink distributor plate 164 where it is picked up by the type inking rolls 105 and rolled on to the type in chase C after passing over the forward ink distributing plate 165.

75 As the rotation of the crank-shaft 70 is 1/2 a cycle out of time with the chain driving shaft 79 the rollers will pass under and deposit ink on

the type in chase C when the printing head 84 is in raised position and continue on until they are beyond the downward path of said printing head 84, which then descends and prints on the paper under it.

80 The web of paper is pulled from the supply roll 26 by the paper tensioning means 27 and the pull-off rolls 247 from which it is fed under the printing head 84 and over the printing bed 46. The web of paper continues on and passes through perforating devices 248 and between paper feed roll 224 and spring-pressed idler rolls 231. At the proper time when the printing head 84 is up and the type inking rolls 105 are putting ink on the type in chase C, the paper is fed a predetermined distance depending on the spacing required between impressions. This spacing of impressions is variable by means of the speed adjusting means illustrated in Figure 25.

85 The web of paper may then be sheared by suitable shearing mechanism indicated at 249, or may be wound on a paper roll-up device 246.

90 It is to be understood, of course, that while the web of paper is at rest any other operations, such as punching, perforating, numbering, etc., may be performed on it.

95 Having now described our invention, we claim:—

1. In a printing press having a printing form and two oppositely facing ink-distributing plates 105 above it, three sets of inking roll units mounted to travel past said form and plates and spaced to cause one unit to apply ink to the form while the other two units are passing over the two ink-distributing plates, and means for supplying ink 110 to one of said two ink-distributing plates.

115 2. In a printing press having a printing form and two oppositely facing ink-distributing plates above it, three sets of inking roll units mounted to travel past said form and plates and spaced to cause one unit to apply ink to the form while the other two units are passing over the two ink-distributing plates, and ink-distributing rolls mounted to travel over one of the ink-distributing plates alternately with said inking rolls.

120 3. In a machine of the character described, mechanism for feeding a web of paper, said mechanism including constantly intermeshed gearing for intermittently advancing the web, the members of said gearing being relatively constructed to gradually increase the speed of the web from stationary condition to a maximum speed and then gradually decrease the speed of the web to stationary condition.

130 4. Mechanism for feeding a web of material, said mechanism consisting of a train of intermeshing gears and a pair of feed rolls, said train of gearing being relatively constructed to gradually increase the speed of the web from stationary condition to a maximum speed and then gradually decrease the speed of the web to stationary condition.

135 5. A flat bed web printing press having mechanism for feeding the web and for operating the printing head and the ink distributor, each of 140 said mechanisms including constantly intermeshed gearing for intermittently actuating the web feed and printing head and ink distributor at speeds starting from stationary and gradually increasing and then gradually decreasing to stationary condition.
